United States Patent Office

Des. 212,093

Patented Aug. 27, 1968

212,093

ENCLOSURE COVER FOR ELECTRIC SWITCH

Woodrow A. De Smidt, Whitefish Village, Wis., assignor to Allen-Bradley Company, Milwaukee, Wis., a corporation of Wisconsin

Filed July 13, 1967, Ser. No. 7,791

Term of patent 14 years

(Cl. D26—13)

FIG. 1.

FIG. 2.

FIG. 3.

FIGURE 1 is an isometric view of an enclosure cover for electric switch;

FIGURE 2 is a plan view thereof;

FIGURE 3 is a side view thereof.

The dominant features of the design reside in the portions shown in full lines.

I claim:

The ornamental design for an enclosure cover for electric switch, as shown and described.
